DESIGN FOR A COAT

Samuel Sandhaus, New York, N. Y.

Application November 3, 1936, Serial No. 65,656

Term of patent 3½ years

To all whom it may concern:

Be it known that I, Samuel Sandhaus, a citizen of the United States of America, residing in Manhattan, county of New York, and State of New York, have invented a new, original, and ornamental Design for a Coat, of which the following is a specification, reference being had to the accompanying drawing, forming part thereof, wherein,

Figure 1 is a front view of a coat showing my new design.

Figure 2 is a rear view of the coat shown in Figure 1.

The characteristic feature of my design resides in the arrangement of the extended split stays on the rear collar portion of the coat, in combination with the graduated arrangement of the stitching on the front collar portion, in combination with the coat, as shown.

I claim:

The ornamental design for a coat, substantially as shown and described.

SAMUEL SANDHAUS.
